UNITED STATES PATENT OFFICE

CHARLES L. WARNER, OF MILFORD, CONNECTICUT, ASSIGNOR TO BAIRD-WARNER, INCORPORATED, OF BRIDGEPORT, CONNECTICUT, A CORPORATION OF CONNECTICUT

OIL BURNER

Application filed December 27, 1930. Serial No. 505,093.

This invention relates to a fuel burning device, and more particularly to an oil burner for use in household heating plants, although of course, it is applicable for use in any location where such a fuel burner is desirable. It is an object of the invention to provide an improved structure for supporting the refractory lining or fire pot bowl which is usually built around this type of burner, which construction is very simple, may be easily formed on the job to fit any size or shape of fire box without any special equipment, and will effectively support the fire pot structure in proper position without danger of sagging or permitting it to fall.

It is also an object of the invention to provide an improved burner construction which will greatly facilitate the mounting and removal of the motor and parts operated thereby for easy renewal, inspection or repair.

Other objects and advantages will appear as the description of the invention proceeds, it being of course, understood that various modifications may be employed without departing from the principles of the invention, reference being had to the accompanying drawings forming a part of this specification.

In these drawings:

Fig. 1 is a vertical section through the fire pot portion of a heater showing my improved burner applied thereto, the burner being shown in side elevation.

Fig. 2 is a partial side elevation and a partial vertical section of the burner on an enlarged scale, the refractory lining being omitted; and

Fig. 3 is a horizontal section through the heater on a plane just above the burner a portion of the structure being broken away to more clearly show the construction.

These liquid fuel burning devices are to a large extent used as replacement structures for solid fuel burning grates and fire boxes in various types, shapes and sizes of household heaters. In setting up these devices after the grate is removed there is usually built about the burner a sort of bowl or lining of refractory material such as brick, clay or sort of fire proof cement, in effect it might be called a fire proof or refractory concrete, packed and

molded on a supporting structure between the burner and the walls of the fire boxes, but as there are a large number of different types and sizes of heaters it is often difficult to properly support and retain this refractory lining in position so that it will not later crack and fall down in use. I have devised an improved structure whereby this lining is properly held in position with no danger of its sagging or falling down, and have so devised it that it may be quickly and easily applied to fit any size or shape of fire box without the necessity of the installing crew carrying any special equipment.

In the drawings is shown at 10 a conventional type of ash pit casting on the upper end of which is supported the heater proper 11. In the present instance the walls of a water heater are shown, but of course, this is merely used for illustration as the device is equally adapted for use in hot air or steam heaters. The device is also shown as having a circular fire box or combustion chamber, but it will be evident from a more complete description that this device is equally adapted for installation in square, oblong or any other shape of fire box. The fuel burning device illustrated comprises a support including a pan or tray 13 supported on the floor of the ash pit by any suitable means such as legs 14. Spaced above this pan or tray is a neck ring 15 having an upright opening 16 therethrough and provided with an outwardly extending substantially horizontal flange 17 having in its top surface a plurality of radially extending recesses or grooves 18. These recesses or grooves may be of various shapes, but are preferably substantially V shaped in cross section as such a shape will automatically and tightly fit and hold any size of pipe or bar which may be mounted therein. These grooves or recesses are adapted to receive the inner end portions of suitable lengths of pipe 19. It is preferred to use pipe for this purpose because when installing these devices pipe must be carried to make the necessary fuel connections with the fuel supply tank and other connections and, therefore, by using this pipe no extra or special equipment need be provided

for or carried by the installing crew, but of course, solid bars may be used if desired. Throughout the specification and claims I have used the word rod as being either a pipe 5 or a solid bar, but ordinarily a pipe will be used as it is stronger for the amount of material it contains and as indicated it does not require any special equipment.

Also extending horizontally therefrom the 10 neck ring is provided with a circumferential rib or flange 20 spaced above the flange 17, and it need not come out as far as the lower flange. This flange carries means for clamping the pipes 19 in the grooves 18 such for 15 example as set screws 21. The whole structure may be greatly strengthened by strengthening ribs 22 and 23. The neck ring is supported above the lower support structure including the tray 13 by any suitable number 20 of upright rods 24.

The fuel burning device also includes the rotary atomizer 25 located above a baffle ring 26 adjustably supported above a ring 27 mounted on the top of the neck ring 15. The 25 supporting ring 27 has an outwardly extending flange 28 resting on the top edge of the ring 15 so that it is securely held thereby but may be removed by merely lifting it from the ring 15. A pair of adjusting screws 29 30 threaded in the ring 27 engage the undersides of the flange 30 of baffle ring 26 and another pair of screws 31 pass through this flange 30 and are threaded into the ring 27. Thus, by adjusting the screws 29 and 31 the baffle 35 ring 26 may be adjusted to the proper height to provide the desired outlet opening 32 for air to support combustion and also to properly level the ring 26. This ring is spaced 40 from the atomizer 25 to provide an air passage 33.

The atomizer 25 is driven by an upright electric motor, the casing of which is indicated in outline at 34. This motor casing has a groove 35 in its lower end to receive the 45 heads of supports 36 carried by coiled springs 37 supported by the tray or support 13. Preferably there are three of these supports 36 equally spaced to give a three point support for the motor. Within the motor assembly 50 is a conduit 38 for leading fuel to the atomizer 25 and the liquid fuel is conducted to this conduit through a flexible conduit 39 connected to the conduit 38 by an easily detachable connection 40. The conduit 39 leads 55 from a cut off valve 41 closed automatically by weight 42 should oil leak down into a pan 43 to operate a trip 44 and release the arm 45 as disclosed more specifically in my co-pending application for oil burner control, 60 Serial No. 504,734 filed December 26, 1930. There is also an automatic electrical control for the liquid fuel indicated at 46 as disclosed in my co-pending application for oil burner control, Serial No. 549,670 filed July 65 9, 1931.

The electrical connection for this control is through the conduit 47 from the connector and junction box 48, the leads from the house system to this box being shown at 49. Another cable 50 leads from this box to the ignition device 51 which is not disclosed specifically herein, and another flexible cable 52 is connected by an easily removable plug connection 53 at the side of the motor casing to lead the necessary electrical energy to the 75 motor.

It will be evident from the description that the motor is supported solely by the spring supports 36, 37 and in an upright position so that it projects upwardly into the opening 16 in the neck ring 15 to position the atomizer 25 at the proper location above this ring. Therefore, in mounting the motor and atomizer in position all that is necessary is to insert the motor down through the opening in the ring 15 from above before the rings 26 and 27 are placed in position. The motor is merely let down through the opening 16 to rest on the supports 36, then the detachable coupling 40 is connected by manipulating the hand screw 40' to connect the fuel supply pipe 39 to conduit 38 and the electrical attachment plug 53 is inserted in the socket in the side of the motor casing. Then after placing the rings 27 and 26 in 95 position on the ring 15 about the atomizer, the device is ready for use. If it is desired to remove the motor and atomizer for inspection, renewal or repair all that is necessary is to pull out the attachment plug 53, disconnect the detachable connection 40 by loosening the screw 41' and lifting off the rings 26, 27. The motor and atomizer may then be removed by merely lifting the motor upwardly through the opening 16 in the ring 15. It will thus be seen that the ring 15 has an unobstructed opening therein of a size to permit easy and free insertion and removal of the motor and atomizer without tearing down the structure or assembly other than removing the rings 26, 27, which can be merely lifted out of position, after detaching the detachable connections 40 and 53. The mounting of the new motor and atomizer and getting it ready for operation can be accomplished in as easy and rapid a manner by a mere reversal of these operations.

In installing the device in the furnace it is mounted in the ash pit after the grate has been removed. The installer then cuts the 110 required number of lengths of pipe 19 from the stock he must carry with him for the necessary fuel connections. These pipes are cut to the proper length to just reach to the inner surface of the fire box at their outer ends as illustrated on the drawings, and these outer ends may rest on and be supported by the grate supporting flange 54 or grate lugs which may remain in position. The pipes are also preferably inclined and rest at their 125 130

outer ends against the inner surface of the fire box as shown so that even tho there is no flange 54 these outer ends will be supported by the walls of the fire box, and as they are inclined the effect of the weight of the lining is to bind these pipes at their outer ends against the surface of the fire box and at their inner ends against the walls of the neck ring or the securing and clamping means 21, thus forming a rigid, strong support which is firmly held in position, and which also retains the burner central in the fire box. Also as indicated above it is preferred that the lower flange 17 extend outwardly farther than the upper flange 20 so that in mounting the pipes in position the outer end can be elevated while the inner end is inserted in the grooves 18 and then the outer end can be lowered to bring it into engagement with the inner surface of the fire box and then clamped in this position by the set screws 21. This assists in easy mounting of the pipes in position and furthermore provides for an adjustment of the pipes so that the outer ends can always be mounted in engagement with the walls of the fire box. The installer then cuts a plate 55 from sheet metal to rest on the top of the pipes 19. This plate may be cut in one piece or in a number of sections as desired and of a shape to fit the shape of the fire box, it extending from the edge of the ring 15 to the inner surface of the fire box walls as shown. Then refractory lining 56 is placed and molded on the top of this plate preferably to substantially the shape shown in the drawings. Thus, it is preferably shaped to form a sort of bowl shaped combustion chamber about the atomizer for a flame indicated at 57 and may be brought to any height desired. It is usually made of fire clay or similar refractory material which is ordinarily tamped and molded in position as a plastic and allowed to harden. It fills the space between the neck ring 15 and the inner wall of the fire box and is brought up to about the top surface of the ring 15 and permits easy removal of the rings 26, 27. This lining prevents direct impingement of the flame on the walls of the fire box, and also after becoming hot assists in complete combustion of the fuel. It closes the space between the ring 15 and the fire box so that the air for combustion passes up through the ring 15. Another important advantage of the pipes 19 extending to and engaging the walls of the fire box at their outer ends is that they properly center the burner and retain it in this position so that it is not forced out of its proper position during the act of firmly tamping the lining 56 in position. In old types of constructions this was a very serious objection because often after the burner was properly placed it was shifted out of position in tamping in the lining and required

tearing out of the lining and re-locating of the burner.

It will be evident that this construction makes a very effective support for the refractory lining which support can be easily constructed and assembled on the job without any special equipment to fit any size and shape of fire box. After the pipe lengths are cut to proper length one end of each is merely inserted in the proper groove 18 and clamped in position by set screw 21 above it. It, therefore, makes a very rigid solid support for the refractory lining and one which will support it in position indefinitely without sagging. As the pipes may be cut to any length desired, this support can be made to fit any size or shape of fire box with no trouble whatever. It is also to be noted that with this construction of burner, the motor and atomizer may be easily and quickly removed without tearing down any of the structure by merely removing the rings 26, 27 and then lifting the atomizer and motor upwardly through the opening 16 in the ring 15, all of which are easily accessible through the usual fuel door, not shown, leading to the combustion chamber. The view of Fig. 1 is from the front so that the ash pit door and fuel door to the combustion chamber would be in the portion of the heater structure which is not shown.

Having thus set forth the nature of my invention, what I claim is:

1. In a fuel burning device, a frame having a laterally extending flange provided with a plurality of recesses therein, laterally extending rods in said recesses, a plate mounted on said rods and supported thereby, a combustion chamber lining of refractory material mounted on the plate, and a means for producing a flame in the combustion chamber.

2. In a fuel burning device, a frame having a laterally extending flange provided with a plurality of radially extending grooves in its top wall, rods seated in said grooves and extending laterally from the flange, means for securing the inner ends of the rods, a plate mounted on and supported by the rods, a lining of refractory material mounted on the plate, and a flame producing means surrounded by said lining.

3. In a fuel burning device, a frame having a substantially horizontal ring provided with a plurality of radially extending grooves in its top surface, a plurality of supporting rods mounted at one end in said grooves and extending laterally from the frame, a flange over the inner ends of the rods, set screws in the flange for securing the rods in the grooves, a plate mounted on the rods, a lining of refractory material mounted on the plate, and a flame producing means surrounded by the lining.

4. In a fuel burning device, a neck ring

having a substantially horizontal flange provided with a plurality of radially extending substantially V-shaped grooves in its top surface, a support for said ring, a plurality of rods seated in said grooves and extending laterally from the ring, said ring also having a flange over the inner ends of the rods, means on said latter flange for securing the rods in the grooves, a plate supported on the rods, a refractory lining on the plate, and a flame producing means extending upwardly through the ring.

5. In a fuel burning device, a support, a neck ring spaced above the support, an upright motor mounted on the support extending upwardly into the ring, a rotary fuel atomizer formed as a part of the motor assembly and located above the ring, the opening in the ring being unobstructed and of sufficient size to permit removal of the motor upwardly through the ring, laterally extending rods carried by the ring, a plate mounted on said rods, and a refractory lining carried by the plate and surrounding the ring.

10. 6. In a fuel burning device, a support, a neck ring spaced above the support, a supporting ring mounted on the neck ring, an upright motor mounted on the support extending upwardly into the neck ring, a rotary fuel atomizer formed as a part of the motor assembly and located above the neck ring, a baffle ring associated with the fuel atomizer and adjustably supported on the supporting ring, a conduit also in said assembly for conducting fuel to the atomizer, a readily detachable flexible connection from a source of fuel supply to said conduit, spring supporting elements for the motor on the support on which the motor rests, said supporting and baffle rings removable as a unit from the neck ring, said neck ring having an unobstructed opening of a size to permit free passage of the motor for mounting on and removing from said elements when the supporting and baffle rings are removed, and a detachable electrical supply connection to the motor.

15. 7. In a fuel burning device, a support, a neck ring spaced above the support, a supporting means mounted on the neck ring, an upright motor mounted on the support extending upwardly into the neck ring, a rotary fuel atomizer formed as a part of the motor assembly and located above the neck ring, a baffle ring associated with the fuel atomizer and adjustably mounted on the supporting means, a conduit also in said assembly for conducting fuel to the atomizer, a readily detachable connection from a source of fuel supply to said conduit, said supporting means and baffle ring removable as a unit from the neck ring said neck ring having an unobstructed opening of a size to permit free passage of the motor for mounting on and removal from the support when the supporting means and baffle ring have been removed, a

refractory lining surrounding the ring and atomizer, and means carried by the ring for supporting said lining.

8. In a heater of the character described, a fire box, a fuel burning device in said fire box including a frame having a laterally extending flange provided with a plurality of laterally extending grooves in its top wall, rods seated in said grooves and extending laterally from the flange, said rods being inclined upwardly toward their outer ends and resting at these ends against the walls of the fire box, a plate mounted on and supported by the rods, a lining of refractory material mounted on the plate, and a flame producing means surrounded by said lining.

10. 9. In a fuel burning device, a frame having a laterally extending flange provided with a plurality of laterally extending grooves in its top wall, rods seated in said grooves and extending laterally from the flange, a lining of refractory material carried by said rods, and a flame producing means surrounded by said lining.

15. 10. In a fuel burning device, a frame having a substantially horizontal ring provided with a plurality of radially extending grooves in its top surface, a plurality of supporting rods mounted at one end in said grooves and extending laterally from the frame, a flange over the inner ends of the rods, said ring being extended outwardly beyond the flange to facilitate insertion of the rods in the grooves, set screws in the flange for securing the rods in the grooves, a lining of refractory material supported by the rods, and a flame producing means surrounded by the lining.

In testimony whereof I affix my signature.

CHARLES L. WARNER.
